H. Wehdeking,

Mangle.

No 70,766.

Patented Nov 12, 1867

H. Wehdeking by his
Attorney W. St. L. Smith.

United States Patent Office.

H. WEHDEKING, OF EDGERTON, OHIO.

Letters Patent No. 70,766, dated November 12, 1867.

IMPROVED MANGLE.

The Schedule referred to in these Letters Patent and making part of the same.

TO ALL WHOM IT MAY CONCERN:

Be it known that I, H. WEHDEKING, of Edgerton, in the county of Williams, and State of Ohio, have invented a new and improved Mangle; and I do hereby declare that the following is a full, clear, and exact description of the construction and operation of the same, reference being had to the accompanying drawings making a part of this specification, in which—

Figure 1 is a plan view.

Figure 2 a side view.

Figure 3 an end view.

Like letters in the different figures of the drawings indicate like parts.

The nature of my invention consists, first, in the arrangement of the arms, rods, holes, and pins in the mangle, for tightening the linen-bed when it has become loose, as well as to enable the ends of the bed to be thrown up out of the way when the mangle is not in use; second, the construction and arrangement of the legs or lower part of the mangle, in combination with the vertical rods, so that the legs may be readily removed in case of a scarcity of room, and the mangle laid on a table, where it may be operated to the same advantage as on the legs; third, the combination and arrangement of the double transverse wooden spring and rubber springs, with the roller, to give a variable movement to the roller to suit different thicknesses of fabric to be passed under it, and to avoid injury to such as have buttons on them.

To enable any one skilled in the art to make and use my invention, I will proceed to describe its construction and operation.

A A A A are the arms, the ends of which are let into the ends of the stationary arms B B, flush with the inner sides of the same. C C are the rods, passed through holes in the arms, and their ends secured by screw-nuts. The rods, passing loosely through the arms A A A A, the arms can be raised, and when down rest on projections formed by letting them in the stationary ones, as above described. a a are holes, one or more being made on each side of the stationary arms, as well as in the movable ones, at a sufficient distance apart to allow the rods to be changed to the proper holes for tightening the linen-bed D, which is formed by stretching and securing the linen over the rollers E E, having pivot ends fitting in holes at the ends of the arms. b b b are the pins, secured to the sides of the stationary arms by short pieces of cord or chain, for fastening the movable arms. The legs are composed of two upright pieces, c' c', on each side of the mangle, and two braces, d d, attached to base-plates e e, and secured crosswise by bars f f, and a rod, g, passed through the base-plates. The upper part of the mangle is also composed of two upright pieces, c c, of the same size as the lower ones, and attached permanently to the stationary arms, immediately in a line over them. Caps h h are placed over the tops of the pieces, and two rods, i i, on each side of the mangle, are inserted down through them, and partially in grooves on the inner edges of the upper and lower pieces, and fastened by screw-nuts under and against the base-plates. The legs are secured to the stationary arms by these rods, the upright pieces of them having small tenons on the tops of them, being slipped into mortises on the under sides of the stationary arms, which prevent them from slipping sidewise. The upper and lower sides of the linen-bed pass over a roller, F, with pivots at each end, resting in boxes set in the stationary arms, between the upright pieces. A crank-handle, G, is attached to the projecting pivot end of the roller, for turning it. Resting on the linen-bed, over this roller, is the roller H, with pivots at each end, and boxes in which the pivots work. On the boxes are the rubber springs I. Across the mangle, and on the boxes, is the double wooden spring J. Hand-screws K K are connected properly with screw-threads in caps h h, which press the springs down on the roller H, and thus regulate the pressure of it upon the fabric, as occasion may require. In practice, the mangle will be provided with extra short rods, so that the legs can be removed when desired, which is done by taking off the nuts and withdrawing the long ones, and then inserting the short rods and fastening them by screw-nuts under the stationary arms. The mangle then may be laid on the table and worked. These rods hold the caps, and serve as guides to the springs and boxes.

Operation: The goods or other articles to be ironed, whether starched or unstarched, are first dampened, as ordinarily, and then placed on the linen-bed, and passed under the roller H, back and forth, by turning the crank-handle, until smooth. Goods wider than the bed can be folded up and smoothed, the same as those of the requisite width. When the bed has become loose, by removing the pins, and throwing up the arms, and changing

the rods to the next holes, and pressing the arms down to their proper places, and fastening them by the pins, the bed will be tightened. When the mangle is not in use the bed may be shortened, so as to be out of the way, by removing the pins and throwing the arms up.

Having thus fully described my invention, what I claim therein as new, and desire to secure by Letters Patent, is—

1. Tightening the linen-bed, and shortening the same, by the arrangement of the arms A A A A, holes $\alpha \alpha$, and pins $b b b b$, in combination with the stationary arms B B, substantially in the manner as herein described and shown.

2. The construction and arrangement of the legs or lower part of the mangle, in combination with the rods $i i$, substantially in the manner and for the purpose as herein described and shown.

3. The arrangement of the wooden spring J, rubber springs I I, rods $i i$, rollers F and H, in combination with the arms A A A A and arms B B, and the legs of the mangle, substantially in the manner and for the purpose as herein described and shown.

H. WEHDEKING.
